UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

DESIGN FOR A CHAIN.

61,359.

Specification for Design. Patented Aug. 15, 1922.

Application filed July 15, 1920. Serial No. 396,615. Term of patent 7 years.

To all whom it may concern:

Be it known that I, REUBEN B. BENJAMIN, a citizen of the United States, residing at Chicago, in the county of Cook and State of Illinois, have invented a new, original, and ornamental Design for a Chain, of which the following is a specification, reference being had to the accompanying drawing, forming a part thereof.

Figure 1 is a side elevation of the chain; and

Figure 2 is a perspective view of portions of adjacent links of the chain.

I claim:

The ornamental design for a chain substantially as shown.

REUBEN B. BENJAMIN.
